(57) **CLAIM**

The ornamental design for an exercise mat, as shown and described.

DESCRIPTION

The patent or application file contains at least one drawing executed in color. Copies of this patent or patent application publication with color drawing(s) will be provided by the Office upon request and payment of the necessary fee.

The sole FIGURE is a top view of the exercise mat of this invention. The sides, ends and back of the exercise mat are not included in the claim. The exercise mat is flat and planar.
